Primary Examiner—Marcus A. Jackson*(74) Attorney, Agent, or Firm*—Knobbe Martens Olson & Bear LLP(57) **CLAIM**

The ornamental design for a taillight assembly, as shown and described.

DESCRIPTION

FIG. 1 is a right side perspective view of the taillight assembly of the present design;

FIG. 2 is a front elevational view of the taillight assembly of FIG. 1;

FIG. 3 is a right side elevational view of the taillight assembly of FIG. 1;

FIG. 4 is a top plan view of the taillight assembly of FIG. 1; and,

FIG. 5 is a right side perspective view of the taillight assembly of FIG. 1, showing the taillight assembly installed on a vehicle.

Phantom lining, where used, is for illustrative purposes only and is not intended to limit the claimed design to the features shown in phantom.
